DESIGN FOR A COMBINED GLOVE, LIPSTICK HOLDER, AND MIRROR DISK

Julius A. Higier, Johnstown, N. Y.

Application October 28, 1941, Serial No. 103,926

Term of patent 3½ years

To all whom it may concern:

Be it known that I, Julius A. Higier, a citizen of the United States of America, residing in Johnstown, county of Fulton, and State of New York, have invented a new, original, and ornamental Design for a Combined Glove, Lipstick Holder, and Mirror Disk, of which the following is a specification, reference being had to the accompanying drawing, forming part thereof, wherein

Fig. 1 is a rear elevational view of a combined glove, lipstick holder and mirror disk, showing my new design;

Fig. 2 is a fragmentary top plan view showing the holder, connecting chain, disk and a portion of the glove shown in Fig. 1;

Fig. 3 is a view similar to Fig. 2 in bottom plan.

The dominant features of the design reside in the portions shown in full lines.

I claim:

The ornamental design for a combined glove, lipstick holder, and mirror disk, substantially as shown and described.

JULIUS A. HIGIER.
